UNITED STATES PATENT OFFICE.

GEORGE R. BRISBEN, OF CLEVELAND, OHIO.

EMERY-WHEEL-DRESSING TOOL.

1,425,941.

Specification of Letters Patent. Patented Aug. 15, 1922.

Application filed December 11, 1920. Serial No. 429,901.

To all whom it may concern:

Be it known that I, GEORGE R. BRISBEN, a citizen of the United States, residing at Cleveland, in the county of Cuyahoga and State of Ohio, have invented certain new and useful Improvements in Emery-Wheel-Dressing Tools, of which the following is a specification.

This invention relates to tools for dressing emery grinding wheels and has as one of its objects to provide a tool having a cutter, the cutting edges of which possess such characteristics of form as to provide for a chipping of the surface of the wheel and a subsequent smoothing or finishing thereof in the same operation so that the grinding wheel may be dressed in an efficient and expeditious manner by the use of a single tool.

Another object of the invention is to so construct the holder for the cutter or chipper of the tool that it may be most conveniently held in position to act upon the face of the wheel to be dressed and will not be liable to become caught or jammed while in use.

25 The invention also has as its general objects to provide a dressing tool which is simple and durable in construction, compact in form, and highly efficient in its operation of dressing the face of the wheel.

30 In the accompanying drawings:

Figure 1 is a top plan view of the tool embodying the present invention;

Figure 2 is a side elevation thereof;

35 Figure 3 is a detail vertical transverse sectional view on the line 3—3 of Figure 2;

Figure 4 is a sectional view on the line 4—4 of Figure 3 looking in the direction of the cutter or chipper of the tool;

40 Figure 5 is a side elevation of one of the chipper elements;

Figure 6 is a sectional view on the line 6—6 of Figure 5 looking in the direction indicated by the arrows;

45 Figure 7 is a detail perspective view of one of the end disks of the chipper assemblage.

Figure 8 is a diagrammatic view illustrating the layout of the periphery of one of the chipping members.

50 The tool embodying the present invention comprises a chipper assemblage and a holder in which the same is mounted, and in the drawings the numeral 1 indicates in general the holder which comprises a handle 2 formed or provided at its forward end with a head indicated in general by the numeral 3. The said head 3 is in the form of a yoke

and comprises a transverse portion 4 which is connected with the handle, and spaced side portions which are indicated by the numeral 5. The side portions 5 are provided with bosses 6 having bearing openings 7 to receive the ends of the spindle upon which the chipper assemblage is rotatably mounted as will be presently pointed out, and the lower sides of the members 5, indicated specifically by the numeral 8, are inclined upwardly and rearwardly as most clearly shown in Figure 2 of the drawings from their toe or rest portions 9 which portions are disposed upon the stationary rest of the 70 grinding wheel in the use of the tool. At this point it is to be noted that when the edges 8 of the said portions 5 are disposed to rest upon the stationary rest of the wheel, the head of the tool holder will be so positioned that the tool cannot become jammed in use. Also because of the form given the head 3, the axis about which the chipper assemblage rotates may be brought closer to the axis of rotation of the grinding wheel as 80 the wheel is dressed and its face is chipped away.

The chipper assemblage is best illustrated in Figures 3 to 7 inclusive and will now be specifically described.

85 The chipper assemblage heretofore referred to comprises a plurality of chipping members certain of which are indicated by the numeral 10 and another by the numeral 10^a, the members 10 being of counterpart 90 form and the member 10^a being somewhat differently formed as will presently be more specifically explained. Generally speaking each of the chipping members comprises a disk-like body 11 provided with an opening 95 12 concentric to the periphery of the member as a whole. In the case of all of the chipping members 10 and 10^a, the body 11 of each is formed upon one face, at points equidistantly spaced about the opening 12, with 100 laterally projecting lugs indicated by the numeral 13 of approximately the same height as the thickness of said body 11. Likewise the body 11 of each of the members 10 is formed at spaced intervals about the 105 wall of the opening 12 with perforations or recesses 14 which alternate with the lugs 13 and which recesses and lugs are of corresponding contour, the recesses being of slightly greater dimensions than the lugs. 110 The member 10^a is not formed with the recesses 14 or their equivalents but on the other

hand is provided upon its face opposite the face upon which the lugs 13 are located, with other correspondingly shaped lugs indicated by the numeral 15 which may alternate with 5 the lugs 13 and which are similarly equidistantly spaced about the opening 12.

There may be any desired number of the members 10 employed in an assemblage of the chippers, and in assembling the members 10 they are disposed side by side in such a manner that the lugs 13 of the members 10 and 10^a will seat or engage in the recesses 14 in adjacent members as clearly shown in Figure 3 of the drawings, one of the members 10 being located at one end of the series and the member 10^a being located at the opposite end. Thus the lugs 13 of the specifically mentioned member 10 will project at 15 one end of the assemblage as there is no corresponding member having recesses 14 to receive these lugs, and likewise while the lugs 13 of the member 10^a will be received in the recesses 14 of the next adjacent member 10, the lugs 15 of this member 10^a will 20 project at the other end of the assemblage. As a part of means provided for holding the members assembled, end disks 15, one of which is clearly shown in Figure 7 of the drawings, are provided and these disks are 25 arranged at the opposite ends of the assemblage and each is formed with a central opening 17 and in the wall of the opening with recesses 18 which are equidistantly spaced about the wall. Returning to a consideration of Figures 3 and 6 of the drawings, it will be observed that the peripheral portions of the members 10 and 10^a are 30 broader than their central or body portions 11 so that in effect depressions 19 are provided in the opposite faces of each member, and in the depression in the outer face of the member 10 which is located at one end of the assemblage, is received the respective end disk 16, the lugs 13 of this member 10 35 seating within the recesses 18 in the said disk. Likewise the other disk 16 is received within the recesses 19 in the outer face of the member 10^a, the lugs 15 of this member seating within the recesses 18 of the 40 respective disk.

In assembling the members 10 and 10^a and the end disks 16, these parts are fitted onto a sleeve 20 one end of which has been previously flanged, as indicated by the numeral 55 21, and after the said parts have been positioned upon the sleeve the other end of the sleeve is overturned or flanged, as at 22, so as to permanently secure the parts in their assembled relation, they being mutually interlocked in the manner above explained. After the parts have been thus assembled, 60 bearing bushings 23 are permanently fitted into the opposite ends of the sleeve 20, and the assemblage is then ready for mounting 65 in the head of the holder. With this end in

view a spindle 24 is fitted through the bores of the bushings 23 as best shown in Figure 3 of the drawings, and the ends of this spindle are seated in the openings 7 formed in the bosses 6 heretofore described. The said 70 ends of the spindle are circumferentially reduced as indicated by the numeral 25, and set screws 26 are threaded downwardly through the outer ends of the bosses 6 and have conical lower ends 27 which seat within the reduced portions 25 of the spindle ends, the spindle being in this manner secured in place both against longitudinal displacement and against rotation.

Referring to the drawings it will be observed that the peripheral portions of the chipping members, which portions are indicated in general by the numeral 28, are formed with radial flutes 29, and referring more particularly to Figures 1 and 8 of the drawings, it will be observed that the flutes 29 are so formed that the chipping periphery of each member will comprise successive portions 30 and 31 which are relatively extended along lines defining angles and curves. 80 Stated in broader terms, the chipping periphery of each member comprises successive portions which are of non-similar linear contour. More specifically speaking each portion 30 of the periphery of each chipping member comprises straight line portions extending at angles to each other, and on the other hand each portion 31 has a linear contour of a compound curve such for example as a cyma curve. The object in view in 85 forming the chipping peripheries of the members with successive portions having different contours is to provide for a more perfect dressing of the face of the grinding wheel acted upon by the tool. Thus the angular portions 30 will relatively roughly chip the face of the wheel along certain lines, and the portions 31 will act upon this face along other lines which however being curved instead of angular, result in a relatively smooth dressing of the face.

The invention also contemplates the provision of a guard for the cutter of the tool, and this guard is indicated in general by the numeral 32 and the same comprises a plate 90 33 pivotally mounted at its rear end upon a pin 34 seated at its ends in lugs 35 upon the forward end of the handle 2 at the upper side thereof. The forward portion of the plate may be widened as indicated by the 95 numeral 36 and, in one position of the guard, extends forwardly and upwardly at an angle over the upper and rear side of the cutter, the said plate being provided with a weighted portion 37 upon its upper side 100 whereby it will normally be held in the position stated, although the plate may be swung rearwardly upon its pivot 34 so as to lie upon the outer side of the handle and 105 out of coactive relation to the cutter.

Having thus described the invention, what is claimed as new is:

1. A cutter element for an emery wheel dressing tool having a chipping edge, successive portions of which include angles and curves.
2. A cutter element for an emery wheel dressing tool having a continuous chipping edge, a portion of which is of rectilinear and angular contour and another portion of which is of curvilinear contour.
3. A cutter element for an emery wheel dressing tool having its peripheral portion fluted, successive pairs of the flutes being respectively of rectilinear and curvilinear contour.
4. A cutter for an emery wheel dressing tool comprising an assemblage of cutter elements, each of said elements having lateral locking lugs and perforations through the body of each of said elements to receive the lugs in adjacent elements, whereby mutual interlocking of said elements is effected.

5. A cutter for an emery wheel dressing tool comprising an assemblage of cutter elements, each of said elements having lateral locking lugs and perforations through the body of each of said elements to receive the lugs in adjacent elements, whereby mutual interlocking of said elements is effected, said lugs being situated on one side of each element.

6. A cutter for emery wheel dressing tools comprising a rotatable element, end disks thereon, cutter elements assembled side by side between said disks, said cutter elements and said disks each being provided with a central aperture for said rotatable element and with equally spaced perforations through the body of each disk and cutter element extending radially from said aperture; said cutter elements having lateral lugs on one side thereof adapted to engage with said perforations.

In testimony whereof I affix my signature. 45
GEORGE R. BRISBEN. [L.S.]
